UNITED STATES PATENT OFFICE.

ALEXANDER HUDSON, OF ROUND LAKE, MINNESOTA.

DESIGN FOR A PHONOGRAPH CABINET.

Application filed April 5, 1927. Serial No. 21,458. Term of patent 14 years.

To all whom it may concern:

Be it known that I, ALEXANDER HUDSON, a citizen of the United States, residing at Round Lake, in the county of Nobles and State of Minnesota, have invented a new, original, and ornamental Design for a Phonograph Cabinet, of which the following is a specification, reference being had to the accompanying drawing, forming part thereof.

Figure 1 is a front elevation of a phonograph cabinet, showing my new design.

Figure 2 is a side elevation of a phonograph cabinet.

Figure 3 is a top plan of a phonograph cabinet.

I claim:—

The ornamental design for a phonograph cabinet, as shown.

ALEXANDER HUDSON.
